UNITED STATES PATENT OFFICE

CHARLES HAMMER, OF HOLLIS COURT BOULEVARD, NEW YORK, ASSIGNOR, BY MESNE ASSIGNMENTS, TO ANCHOR CAP & CLOSURE CORPORATION, OF LONG ISLAND CITY, NEW YORK, A CORPORATION OF NEW YORK

ROTARY CAP HAVING SEALING MATERIAL FLOWED THEREINTO

Application filed December 21, 1928. Serial No. 327,602.

The present invention relates to closures or caps for containers, and more particularly to rotary caps adapted for the hermetically-sealing of glass containers.

Heretofore it has been the practice to provide rotary caps, either with a separate liner plate or a ring formed gasket. These forms of vacuum-sealing material required a comparatively thick material to preserve its shape, which materially increased the cost of the cap. As there was no way to lock such separable sealing members in place; consequently after the container was sealed, it was necessary to retighten the cap by giving it a further turn-on in order to efficiently clamp the cap onto the container. In other words, after the sealing material and cap had been applied to the container and the cap vacuum-sealed, it was found that the cap was loose and this required the further turning of the cap onto the container efficiently to clamp the cap on the sealing material. This required considerable time and therefore increased the expense, and furthermore, there were times when the cap was not thoroughly tightened by this subsequent turning operation and consequently the container was not tightly sealed.

Attempts have been made to pour sealing material into caps with more or less success, but experiments have disclosed that this mode of applying the sealing material to a rotary cap is not successful because on the rotation of the cap, the sealing material wrinkles and prevents the efficient sealing of the container. In fact I was advised that it was not possible to use a fluid sealing material flowed into the cap when that cap was a rotary cap because it would not hold and would wrinkle and therefore interfere with the efficient sealing of the container. But by reason of the present improvement, I have made it possible to use such a sealing material in rotary caps to such an extent that many hundred thousand of these caps have been successfully manufactured and used, and it is now claimed by many prominent packers that it is the best vacuum-sealed cap ever placed on the market, and therefore I believe that I am the first to provide a practical and com-

mercial rotary type of cap with sealing material flowed thereinto,—since by this improvement, the sealing material is so securely held within the cap that the rotation thereof to the fullest extent in the first instance does not affect either the position or the condition of the sealing material or cause it to move relatively to the cap. 55

An object of the invention is to provide an inexpensive rotary cap with an improved sealing material secured therein practically integral with the cap. 60

Another object of the invention is to decrease the cost of a cap adapted to form a hermetic seal by reducing the amount of sealing material without impairing or decreasing the effectiveness of the seal. 65

Another object of the invention is to provide a successful commercial rotary cap having a small quantity of sealing material flowed thereinto which will not wrinkle upon rotating the cap about the container. 70

Another object of the invention is to provide an improved closure cap with a recessed annular band having sealing material flowed thereinto and said band having a grooved annular portion therein to increase the surface area of the sealing material in contact with the cap thereby giving the sealing material a better grip on the cap. 75 80

Another object of the invention is to provide an efficient rotary cap having a layer of sealing material flowed therein which will form a hermetic seal when applied upon a container. 85

A further object of the invention is to provide a rotary cap with a sealing layer that will prevent the cap from accidental rotation after once being applied, thereby eliminating the necessity of re-tightening the cap. 90

A still further object of the invention is to provide a rotary sealing cap with sealing material flowed thereinto which is adapted to be used to reclose the receptacle tightly to prevent the loss of the contents by spilling or spoiling. 95

Other and further objects of the invention will be obvious upon an understanding of the illustrative embodiment about to be described or will be indicated in the appended 100

claims, and various advantages not referred to herein will occur to one skilled in the art upon employment of the invention in practice.

5 A preferred embodiment of the invention has been chosen for purposes of illustration and description and is shown in the accompanying drawings, forming a part of the specification, wherein

10 Fig. 1 is a top view of the cap;

Fig. 2 is an interior view of the cap with the sealing material applied thereto;

Fig. 3 is a cross-sectional view of the cap shown in Fig. 2;

15 Fig. 4 is a view of the under or rear side of the sealing material; and

Fig. 5 is a cross-sectional view thereof, enlarged;

20 Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description 30 and not of limitation.

This improved cap, which is shown of metal, may comprise a top 2, having a depending skirt 3 provided with a strengthened or re-enforced lower edge 4, usually obtained by curling or beading the lower edge. This lower edge is provided with locking lugs 5 formed from the bead, these lugs being shown as arc-shaped. The skirt is also provided with re-enforcing corrugations 6 40 which together with the bead assist materially in strengthening the skirt of the cap, while these corrugations also provide a hand grip and efficient means for the rotation of the cap on the forming rolls. The top of 45 the cap is provided with a panel 7 shown as of concavo-convex form terminating at its outer edge in a tapered or inclined surface 8 forming therebetween and the skirt an annular channel, recess or groove 9 of relatively wide dimensions and of sufficient width 50 to receive therein the sealing material according to the width thereof to be used.

It has been found, however, that the sealing material poured into a rotary cap wrinkles, becomes dislocated and interferes with the proper sealing of the container on the rotation of the cap. To avoid this, I provide the cap with an annular, outwardly or upwardly extending rib forming groove 10, of less width than the annular recess or groove 9, terminating adjacent to the skirt in an annular shoulder 9'. Heretofore it has been the practice to form the cap with an annular projection or rib extending 65 downwardly or into the cap for the purpose

of engaging the sealing material immediately over the mouth of the container. In the present improvement, however, this annular rib forming groove extends upwardly and is wedge formed.

70 In practice the sealing material 11, which is called compo, is poured into the cap in a fluid condition and permitted to flow into the relatively wide groove 9 where it forms

75 a ring and sets, and by reason of its adherent character and the locking rib groove 10 it is efficiently held in the cap so that it is practically integral therewith, the setting of the material causing it to conform to the shape

80 of the two grooves so that the sealing material thus has an interlocking rib 12, as shown in Fig. 5, projecting into the smaller groove 10 which acts to hold the compo from

85 moving laterally or wrinkling when the cap is firmly turned down by machinery onto the container. The use of compo material for

90 sealing the container is very much more advantageous than an ordinary ring gasket or liner plate or any other form of gasket so far known, by reason of the fact that it

95 can be relatively thin so that a small quantity will efficiently accomplish the purpose desired, thus materially reducing the expense while at the same time it more efficiently seals the container and also prevents as herein-

100 before stated the necessity of retightening the cap after it has once been applied, thereby reducing the labor cost. It will be observed that the inclined part 8 and the inner skirt wall 3 together with the locking groove

105 10 which has a depth substantially equal to or greater than the depth of the recess also co-act together with the adherent qualities of the compo as to securely hold it firmly in place against mutilation or wrinkling during the rotation of the cap to any degree

110 desired, so that the cap may be readily reused as often as desired, especially as the compo cannot become separated from the cap and lost, as is frequently the case with ordinary ring gaskets or liner plates.

115 As various changes may be made in the form, construction and arrangement of the parts herein without departing from the spirit of the invention, it is to be understood that all matter herein is to be interpreted as

120 illustrative and not in a limiting sense.

Having thus explained the nature of my

125 said invention and described a way of constructing and using the same, although without attempting to set forth all of the forms

130 in which it may be made or all of the modes of its use, I claim:

1. A sealing cap comprising a cover part, a depending skirt, a plurality of concentric grooves in the cover portion of said cap, and sealing material common to said grooves, said grooves co-operating with each other to hold the sealing material in position.

2. A rotary vacuum sealing cap comprising a cover part, a depending skirt, a plurality of concentric grooves in the cover portion of said cap, and sealing material flowed into said grooves, said grooves co-operating with each other to hold the sealing material in position. 70
3. A rotary vacuum cap comprising a cover portion, a depending skirt, an annular groove in the cover portion of the cap adapted to receive sealing material, said groove having a portion of the bottom thereof depressed to receive the sealing material and to hold it in position in said groove, and sealing material flowed into said groove and into said depressed part. 75
4. A rotary vacuum sealing cap provided with an annular groove adapted to receive sealing material, an auxiliary groove within said annular groove, and sealing material flowed into said grooves and held in position thereby. 80
5. In a rotary vacuum sealing cap, the combination of a cover portion, a depending skirt, an annular groove adjacent the outer periphery of said cover portion for holding sealing material adapted to engage the rim of a container, an auxiliary groove within said annular groove and located adjacent the outer edge thereof, and sealing material flowed into said groove and held against displacement thereby. 85
6. A vacuum-sealing cap having an annular groove, provided within the same with an annular groove of less width, and a sealing compound flowed into said grooves and adhering to the top and interlocked therewith against shifting movement within the cap, whereby the cap may be tightened down without injury to the sealing compound. 90
7. A vacuum-sealing rotary cap having its top provided with an annular recess of relatively wide dimension and within the same a relatively narrow groove projecting outwardly therefrom and located adjacent to the skirt of the cap, and a sealing compound flowed into said grooves and adhering to the top and so interlocked therewith against shifting movement relatively to the top whereby the cap may be tightened without injuring the sealing compound. 95
8. A vacuum-sealing cap comprising a top and a skirt, said top having an inwardly projecting panel forming a relatively wide annular recess having its top wall provided with a groove of relatively narrow width, and a sealing material flowed into said recess and groove and locked against shifting thereby with its sealing face substantially flush with the inner face of the panel. 100
9. A vacuum-sealing rotary cap comprising a top and a skirt, said top having an inwardly projecting panel forming a relatively wide annular recess having a beveled or inclined side wall and having its top wall pro- 105
- vided with a groove of relatively narrow width, and a sealing material flowed into said recess and groove and locked against shifting thereby with its sealing face substantially flush with the inner face of the panel. 110
10. A vacuum-sealing rotary cap comprising a top and a skirt, said top having an inwardly projecting panel forming a relatively wide annular recess having its top wall provided with a wedge formed groove having a depth substantially equal to or greater than the depth of the annular recess and of relatively narrow width, and a sealing material flowed into said recess and groove and locked against shifting thereby with its sealing face substantially flush with the inner face of the panel. 115
11. A vacuum-sealing rotary cap comprising a top and a depending skirt, said top having an inwardly projecting panel provided with an inclined side wall forming with the skirt an annular recess, the top of said recess having an outwardly projecting annular rib forming groove connected with the skirt by a shoulder, and a sealing material flowed into said recess and groove and so adhering to the cap and locked within the recess and groove as to permit the cap to be tightened down without the wrinkling or dislocation of said sealing material. 120
12. A vacuum-sealing rotary cap comprising a top and a depending skirt, having corrugations and a curled bead provided with inwardly projecting locking lugs, said top having an inwardly projecting panel provided with an inclined side wall forming with the skirt an annular recess, the top of said recess having an outwardly projecting annular rib forming groove connected with the skirt by a shoulder, and a sealing material flowed into said recess and groove and so adhering to the cap and locked within the recess and groove as to permit the cap to be tightened down without the wrinkling or dislocation of said sealing material. 125
13. A closure cap adapted to form a hermetic seal with a glass container, comprising a top and a skirt, said top having a relatively wide, annular channel adjacent the periphery thereof, an auxiliary groove substantially centrally disposed with respect to said channel, and sealing material flowed into said channel and into said groove whereby it is firmly locked in position. 130
14. As an article of manufacture, a vacuum cap adapted to form a hermetic seal with a glass container, comprising a top and a skirt, said top having an upwardly extending annular groove adapted to receive sealing material, certain portions of said groove being substantially deeper than other portions thereof, and sealing material flowed into said cap and into said groove, whereby the deeper portions of the groove cooperate with the groove to hold said sealing material in position. 130

15. As an article of manufacture, a screw cap adapted to form a hermetic seal on a glass container, comprising a top and a skirt, said top having a groove therein adjacent its periphery to receive sealing material for engaging with the rim of a glass container, and means comprising deformation of the metal in the bottom of said groove adapted to receive the sealing material flowed into the groove and also adapted to cooperate with the groove to hold the sealing material in position, and sealing material flowed into said groove.

Signed at Brooklyn, N. Y., this 19th day
15 of December, 1928.

CHARLES HAMMER.
